UNITED STATES PATENT OFFICE

2,190,738

ANTISTALL DEVICE

Joseph Schweiss, St. Louis, Mo., assignor to
 Carter Carburetor Corporation, St. Louis, Mo.,
 a corporation of Delaware

Application September 19, 1938, Serial No. 230,716

3 Claims. (Cl. 123—103)

This invention relates to carburetors for internal combustion engines and consists particularly in a novel antistalling device therefor.

Devices have been suggested which utilize intake manifold suction to slightly open the carburetor throttle valve whenever the suction in the engine intake system drops excessively. These devices hold the throttle valve open when there is no suction in the intake system, or in other words, when the engine is inoperative and thus cannot be used in carburetors having "anti-percolating" mechanism, as described, for instance, in Moseley Patent No. 2,013,787. This mechanism requires full closing of the throttle valve when the engine is inoperative in order to open a vent for relieving vapor pressure formed at the base of the main nozzle and prevent the gasoline from spilling into the intake manifold.

It is an object of the present invention to provide an antistall device which may be utilized with a carburetor embodying antipercolating mechanism as described in the Moseley patent.

Another object is to provide an antistall device which is constructed and arranged to insure slight opening of the throttle valve when the suction in the engine intake system drops sufficiently to indicate that the engine will stall if the throttle valve is permitted to fully close, but which permits full closing of the throttle valve at all other times.

These objects and other more detailed objects hereafter appearing are attained substantially by the structures illustrated in the accompanying drawing in which:

Fig. 1 is a side view of a portion of an internal combustion engine intake system including the carburetor and a part of the intake manifold, with the invention applied thereto.

Fig. 2 is a detail section taken substantially on line 2—2 of Fig. 3.

Fig. 3 is a detail side view and section taken substantially on line 3—3 of Fig. 1.

Fig. 4 is a side view and section illustrating a modification.

Fig. 5 is an enlarged diagrammatic view illustrating a part of the structure in Fig. 4.

Fig. 6 is a view showing a part of the structure in Fig. 2, but in a different position.

Fig. 1 illustrates a downdraft carburetor including a barrel portion 1, flanged at its lower end as at 2 and attached by means of bolts 3 to the intake manifold 4, the usual "hot spot" 5 being provided. The usual constant level chamber 6 is located adjacent barrel 1. Pivotally mounted on shaft 7 near the lower portion of

barrel 1, is a butterfly-type throttle valve 8. Shaft 7 projects beyond both sides of the barrel and at one end carries an arm 9 for connection to the usual accelerating pump (not shown) by means of a link 9a and lever 9b. A lever 10 rigid with the other end of shaft 7 has two pairs of outstanding threaded lugs 11 and 12 mounting stop screws 13 and 14. Lever 10 is perforated at one end as at 15, for attachment to the usual manual control mechanism connected to the accelerator pedal.

A bracket 16 is mounted between the carburetor flange and manifold and at its outer end carries a suction device generally indicated at 17. Device 17 includes a diaphragm 18 normally urged to the right by a coiled spring 19 (see Fig. 4). A tube 20 connects the device with the intake manifold suction. A guide tube 21 extends horizontally from the suction device and slidably receives a rod 22 secured to the diaphragm and having at its outer extremity annular ridges 23, 24 and 25 with recesses 26 and 27 therebetween. A small hole or recess 28 in the upper wall of tube 21 near the outer end thereof receives a loose ball plunger 29 which is in position to be engaged by screw 14 on lever 10.

In operation, suction device 17 is constructed to insure the maintenance of diaphragm 18 in its left hand or inward position whenever normal operative suction exists in the intake manifold, this including the lowest suction which prevails when the throttle valve is substantially closed and with the engine continuing in operation. Spring 19 is calibrated to move diaphragm 18 and rod 22 to the right only when the intake suction approaches zero so as to indicate that the engine is about to stall unless the throttle valve is opened. In such case middle ridge 24 on rod 22 is moved under ball 29, as shown in Fig. 6, raising the same into the path of screw 14 so as to prevent full closing of the throttle valve or to open the valve slightly if it is already closed. When the speed of the engine again picks up, diaphragm 18 is drawn to the left permitting ball 29 to drop into recess 27. When the engine stops operating and there is no suction in the intake system, spring 19 forces rod 22 fully to the right permitting ball 29 to drop into recess 26, as in Fig. 2. This permits full closing of the throttle valve and, consequently, opening of the anti-percolator vent, as described in the above mentioned Moseley patent. Screw 14 is adjusted so as to just clear ball 29 when the latter is in either of the recesses 26 or 27. Screw 13 cooperates with a stop 30 on the outside of barrel 1 to limit

the closing movement of the throttle valve to its normal idling position.

In Figs. 4 and 5 is shown a modification utilizing a suction device 17 as in the previous form.

- 5 A lever 35 is pivoted at 36 to carburetor barrel 1 and a bell crank lever 37 is pivotally connected to the lower extremity thereof, as at 38. Lever 37 has a curved slot 39 in the lower portion thereof slidably receiving a pin 40 projecting from lever 10a on throttle shaft 7. Diaphragm actuated rod 22 is pinned to the end of lever 37 opposite slot 39.

Whenever normal operating suction exists in the intake system, levers 35 and 37 will be held 15 in the disaligned, solid line position shown in Fig. 5, which permits full closing of the throttle valve. However, in case the intake suction drops sufficiently to indicate an impending stall, the 20 throttle being closed, the consequent movement 25 of diaphragm 18 to the right will cause levers 35 and 37 to become substantially aligned, as indicated in solid lines in Fig. 4. This alignment of the toggle levers moves the upper edge of slot 39 slightly downwardly so as to engage pin 40 and prevent full closing of the throttle valve, or open the valve. When there is no suction in 30 the intake system, toggle levers 35 and 37 will be moved to a disaligned position opposite the solid line position in Fig. 5, again permitting full closing of the throttle valve.

Fig. 5 indicates diagrammatically the three positions of toggle levers 35 and 37 which permit free opening movement of the throttle valve at 35 all times and also permit full closing of the valve except when the suction in the intake system drops to a point to indicate that the engine is about to stall.

The novel antistall device may be used with 40 substantially any type of carburetor and, although, an important advantage of the device is obtained when it is used with an anti-percolating device as disclosed in the above-mentioned Moseley patent, the device has other advantages and may be used where no anti-percolator is provided. The specific form of suction responsive 45 device shown is not essential. The structure shown may be modified in the above and other respects as will occur to those skilled in the art

and the exclusive use of all such modifications as come within the scope of the appended claims is contemplated.

I claim:

1. In combination with internal combustion engine intake conduit including a carburetor having a throttle valve and an operating arm therefor, a device responsive to suction in said conduit, a lever pivoted adjacent said mechanism, a second lever pivotally connected to said first lever and 10 having a slot, said arm having an element movable in said slot and said levers forming a toggle, and a rod operated by said device and connected to one of said levers intermediate the ends of the toggle so as to disalign said levers when there 15 is normal operating suction and when there is no suction in said mechanism and to substantially align said levers when the intake pressure approaches atmospheric, said throttle arm element being freely movable in said slot to permit full 20 opening and closing of said throttle valve when said levers are disaligned but cooperating with an end of said slot when said levers are aligned to insure at least partial opening of said throttle valve. 25

2. In combination with an internal combustion engine intake conduit including a carburetor having a throttle valve and operating mechanism therefor, a device responsive to suction in said conduit, a guide projecting from said device having a recess adjacent said mechanism, a plunger in said recess, and a rod connected to said device and movable thereby along said guide, said rod having a raised portion for engaging said plunger when the intake pressure approaches atmospheric 35 to move the same into the path of said mechanism to insure at least partial opening of said throttle valve and said rod having recessed structure adjacent said raised portion to permit full closing of said throttle when the intake suction 40 fails. 30

3. The combination of elements specified in claim 2 in which said recessed structure is constructed and arranged to permit full closing of said throttle valve when normal operating 45 suction exists in said intake conduit.

JOSEPH SCHWEISS.
